BY

James J. Steele, C. ATTORNEYS.

UNITED STATES PATENT OFFICE.

ABRAHAM LIBERMAN, OF CLEVELAND, OHIO.

STOVE APPLIANCE.

Application filed May 13, 1924. Serial No. 713,085.

To all whom it may concern:

Be it known that I, ABRAHAM LIBERMAN, a citizen of Poland, residing at Cleveland, in the county of Cuyahoga and State of 5 Ohio, have invented new and useful Improvements in Stove Appliances, of which the following is a specification.

My present invention pertains to attachments for gas stoves of the natural or artificial type and it contemplates the provision of a safety appliance through the medium of which should the gas that is flowing to the burners be extinguished the flow of said fuel to said burners will be automatically 15 discontinued.

The invention further contemplates the provision in a gas stove of a safety attachment that is positive in operation and functions by the flow of gas itself if for any 20 reason ignition of the gas at the burner rings is interrupted.

Other objects and advantageous features of the invention will be fully understood from the following description and claims 25 when the same are read in connection with the drawings accompanying and forming part of this specification in which:—

Figure 1 is a top plan view of my novel stove and showing same provided with two 30 burner units and the safety gas cock attachments.

Figure 2 is a vertical section of the stove and showing the various elements in normal position that comprise my safety attachment.

Figure 3 is a view similar to Figure 2 but showing the position the elements assume when the flow of gas to the ignition point of the burners is interrupted.

Figure 4 is a longitudinal sectional view of the burner used in the units and taken on the line 4—4 of Figure 5 looking in the direction of the arrows.

Figure 5 is a horizontal sectional view taken in the plane indicated by the line 45 5—5 of Figure 4.

Similar numerals of reference designate corresponding parts in all the views of the drawings.

My novel stove is indicated by 1 and may be of the type illustrated or any other type suitable to its purpose and the stove illustrated comprises a front wall 2 and a rear wall 3 and arranged in the stove is a plate 50 or support 4 and provided at the usual

point adjacent the front wall 2 is the ordinary well known inlet fuel supply pipe 5.

Mounted in any approved manner on the support 4 are my novel burner rings 6 and arranged on the supply pipe 5 are the gas-kets 7 and adapted to operate the ordinary gas cock are handles 8 and depending from the handles or cocks 8 is a downwardly extending leg 9 while secured to the front wall 2 at one end and the leg 9 at the opposite end is a spring 10. Manifestly the leg 9 will travel in an arc with respect to the front wall of the stove. Arranged below the leg 9 is a toothed semi-circular rack 11 that is adapted to normally engage the 70 lower end of the leg 9 and retain same in open position against the action of the spring 10 and the said rack 11 is arranged on the extreme outer end of a bar 12 that rests below the support 4 and is pivoted at 75 13 and arranged in the front and rear walls 2 and 3 are slots 14 and 15 respectively whereby play upwardly and downwardly of the bar 12 is permitted.

Extending from the main gas supply pipe 80 5 are the inwardly directed feed pipes 16 that connect with the burners 6 while extending from the rear of the burners are the pipes 18 that are flared at 17 for an important purpose hereinafter set forth.

As will be readily seen by reference to Figures 2 and 3 the pipes 18 connect with the T-pipe 19 and communicating with the said pipes 19 is a bellows 20 provided on its upper end with a bulb 21.

Pivoted at 26 on the bracket 24 is a member having a flat base portion 22 and arranged on one end of this member is a housing 23 in which is arranged a ball 24' that rests within the housing 23. The said member as before stated is pivoted at 26 by means of a saddle 27 while arranged adjacent a bracket 24 is a bracket 28 on which the pivoted member 30 is journaled at 29.

The pivoted member 30 is provided with 100 the noses 31 and 32 respectively. Arranged below the flat base 22 is a lateral rod 34 that is connected with a bar 33 that extends the full length of the stove and is provided with the handle 35.

As shown in Figures 4 and 5 the burners 6 consist of the main body portion 37 having the cap 38 and at one end I provide an inlet 39 and the said burners are provided with the apertures 40 while arranged to 110

communicate with said apertures 40 are the projections 41 that are hollow throughout and communicate with the burner apertures 40. These projections 41 may be of any number and they are provided with the slots or channels and arranged so as to direct gas to the flared mouth 17 of the pipes 18 are a series of projections 42 as illustrated. By the arrangement of the members 10 41 and 42 gas while burning will be sucked up through the projections 41 because of the natural affinity of gas for flame but if the gas is extinguished the projections will cause the gas to be spread around the interior of 15 the burners to the flared mouth above referred to. When desired a baffle having a small opening at its base may be arranged immediately in rear of the projections 42 and preferably within the flared mouth 17 20 and when such a device is used back draught and the consequent driving of unburned gas back into the burners will be effectually precluded.

The working elements of the device are 25 confined within the cabinet 43 that is mounted in rear of the stove.

In the practical operation of the device the handle 8 of the feed pipe 16 is moved 30 to permit flow of gas to whichever burner it is desired to light. The arm 9 will ride along the arcuate toothed rack 11 and said arm will prevent the spring from pulling of the handle 8 back to its closed position. If for any reason, the flame should become 35 extinguished, the gas because of the projections 41 and 42 will be forced to travel into the flared mouth 17 down the pipe 18 to pipe 19 and will inflate the bellows 20 with the consequent inflation of the bulb 21. Normally the device and the working elements 40 thereof retain the normal position shown in Figure 2 but when the inflation before set forth takes place, the working elements will assume the positions shown in Figure 3. 45 Inflation of the bulb 21 will cause the flat base 22 to cant or pivot on the support 24 and the ball 24' will travel to the forward end of the casing 23 causing the lower end thereof to move the nose 31 downwardly 50 and rock the member 30 on the support 28 and consequently lift the nose 32 which in turn bears on the end of the rod 12. This action will cause one end of the rod 12 to move upwardly and the pivoting of the rod 55 at 13 will force the outer end of said rod downwardly thereof disengaging the toothed rack 11 for the leg 9. This will manifestly permit the spring 10 to pull the handle toward the front wall 2 of the stove thereby 60 automatically cutting off the flow of gas to the burner.

The device comprises an extremely small number of elements but said elements are so constructed that the liability of same becoming inoperative after a short period of use

is eliminated. It will be readily appreciated that positive operation of the device will take place if for any reason the burner is extinguished and at the same time flow of the gas to the flared mouth is also assisted because of the well known fact that the heated gas will travel to the burners and the outlets thereof while cold gas or that which does not reach the burner outlets will naturally travel downward and eventually 75 to the flared mouth 17.

The ball 24' assists in both downward and upward movement of the casing 23 and the return of the casing to its normal position is accomplished by simply turning the handle 80 35 so as to cause rod 34 to push against the casing 23 and force same upwardly to the position shown in Figure 2.

I would distinctly have it understood that I do not wish to be confined to any particular size, shape or material of the elements employed in my device for the reason that I reserve to myself the right to make such changes and modifications in the future construction and practical use of said invention 85 90 that fairly fall within the scope of my appended claims.

Having described my invention, what I 95 claim and desire to secure by Letters-Patent is:—

1. In a safety appliance for stoves, the combination of a burner having tubular projections arranged therein and adapted to communicate therethrough with the burner openings, inlet pipes to the burners, cocks arranged on the inlet pipe, springs secured to the cocks and to the front wall of the stove, a leg secured to the cocks, a flared mouth arranged to communicate with the burners, means for diverting unburned gas 100 from the burners to the flared mouth, a pipe secured to the flared mouth, a bellows secured to one end of the pipe, a ball arranged on the end of the bellows, a bracket arranged adjacent the bellows, a pivoted 105 member arranged on the bracket and having a casing on one end in which a ball is confined, a second bracket arranged adjacent the first bracket, a saddle arranged on the second bracket and having upwardly 110 extending ends, a rod pivotedly arranged below the burners and having one end adapted to be actuated by one of the projections of the saddle, a toothed rack arranged on one end of the rod and adapted 115 to normally engage the lower end of the leg of the cock, and means for returning the casing that contains the movable ball to its normal position.

2. In a safety appliance for gas stoves 125 and the like, the combination of burners, feed pipes communicating with the burners, means arranged within the burners for directing gas that is continuously igniting in one direction and gas that is not ignited 130

at the burners, in a rearward direction away from the burner holes, a cock for controlling the supply of gas to the burners, means for normally holding the cocks in open position and other means for automatically returning the cocks to their closed positions and comprising a pipe having a bellows and bulb communicating therewith, a rocking platform actuatable by the bulb, a second platform actuatable by the first platform in one direction and a rod actuatable by the second platform in one direction to release the lower end of the cocks and means for returning the platforms and rod to their normal position.

3. In a safety appliance for gas stoves, the combination of burners, tubular projections arranged within the burners and communicating with the burner holes, cocks for controlling the supply of gas to the burners, a spring for placing the cocks under tension when open and a bar having a rack that engages a portion of the cocks to retain them in open position, a bellows having a bulb actuatable when the flow of gas is interrupted to the burner outlets, a platform actuatable by the bulb and adapted to actuate a second platform that in turn actuates the rod on which the rack is arranged and means for returning the rod to its normal position.

4. In a stove, the combination of burners a main gas supply pipe arranged in front of the burners, a valve for controlling the supply of gas to the burners, a leg secured to the valves, a spring secured to the leg for placing same under tension when the valve is open, a rod pivotedly mounted below the burners and having a rack that engages the leg of the valve, a bulb mounted on one end of a bellows and adapted to be inflated by gas, from the burners, that does not reach the burner openings, a pivotedly platform movable by the bulb, a casing secured to the platform, a marble arranged in the casing, a member having upturned portions at each end pivotedly mounted below the casing and movable in one direction thereby; said last named member being adapted to actuate the arm on which the rack is mounted, and means for returning the working elements to their normal position, substantially as and for the purpose specified.

In testimony whereof I have hereunto set my hand in presence of two subscribing witnesses.

ABRAHAM LIBERMAN.
